(57) **CLAIM**

The ornamental design for a clip, as shown and described.

DESCRIPTION

FIG. 1 is a top perspective view of my design for a clip;

FIG. 2 is a top view thereof;

FIG. 3 is a front end view thereof;

FIG. 4 is a rear end view thereof;

FIG. 5 is a left side view thereof;

FIG. 6 is a right side view thereof;

FIG. 7 is a bottom view thereof; and,

FIG. 8 is a top perspective view thereof, with the clip inserted into a holder.
The areas shown in broken lines show environmental structure and form no part of the claimed design.
